TABLE LEG

Morton R. Cohen, Chicago, Ill.

Application February 29, 1956, Serial No. 40,415

Term of patent 14 years

(Cl. D33—15)

FIG. 2

FIG. 1 FIG. 5

FIG. 3

FIG. 4

Fig. 1 is a front elevational view of a table leg showing my new design;

Figs. 2 and 3 are, respectively, magnified bottom and top plan views of the table leg;

Fig. 4 is a fragmentary rear elevational view of the portion of the table leg which includes the decorative connecting element; and

Fig. 5 is a side elevational view of the table leg as shown in Fig. 1.

I claim:

The ornamental design for a table leg, as shown.
